UNITED STATES PATENT OFFICE.

GÜNTHER PHILIP WILD, OF PHILADELPHIA, PENNSYLVANIA, ASSIGNOR TO FREDERICK W. SCHMIDT, OF PHILADELPHIA, PENNSYLVANIA.

THERMOSTAT.

1,012,952.

Specification of Letters Patent. Patented Dec. 26, 1911.

Application filed December 2, 1910, Serial No. 595,284. Renewed November 6, 1911. Serial No. 658,874.

To all whom it may concern:

Be it known that I, GÜNTHER PHILIP WILD, a citizen of the United States, residing in the city and county of Philadelphia, 5 State of Pennsylvania, have invented a new and useful Thermostat, of which the following is a specification.

My invention consists of certain improvements in a thermostat particularly adapted 10 for use in a controlling apparatus for charging storage batteries, such as disclosed in patents, Nos. 976,748 and 976,750, granted to Frederick W. Schmidt, on the 22d day of November, 1910.

15 It further consists of a thermostat capable of functions and possessed of properties similar to those performed and possessed by the thermostats for which Letters Patent Nos. 976,747 and 976,749, were granted to 20 Frederick W. Schmidt, on the 22d day of November, 1910.

It further consists of a thermostat having 25 a casing composed partly of electrically conductive and partly of electrically non-conductive but acid-resisting materials.

It further consists of a thermostat for such purpose and in which the casing is composed of an acid-resisting and non-conductive material having electrodes of acid-resisting and electrically conductive material 30 extending through the casing to the elements of the thermostat.

It further consists of other novel features of construction, all as will be hereinafter 35 fully set forth.

For the purpose of illustrating my invention, I have shown in the accompanying drawings one form thereof which is at present preferred by me, since the same has 40 been found in practice to give satisfactory and reliable results, although it is to be understood that the various instrumentalities of which my invention consists can be variously arranged and organized and that 45 my invention is not limited to the precise arrangement and organization of these instrumentalities as herein shown and described.

Said drawing represents a longitudinal 50 section of a thermostat embodying my invention.

The thermostat consists of a metallic base-plate, 1, usually of brass, having a short post, 2, at one end, into which one end of a

composite metal thermostat-bar, 3, is 55 secured. The free end of said bar has a contact-point, 4, preferably of a metal fusible at a high temperature, only, which registers and may have contact, when the bar is flexed owing to the difference in the co-efficients 60 of expansion of the two metals from which the bar is formed, with a contact-point, 5, of the same metal and secured to the end of a contact-screw, 6, threaded, to be adjusted with its point nearer to or farther from the 65 contact-point of the thermostat-bar, in a yoke or bracket, 7, secured upon but insulated from the base-plate. The base-plate and thermostat is inclosed within the body, 8, of a casing, preferably of rectangular 70 form, and having its top closed by a cover, 9, secured with its edges in rabbets, 10, in the upper edges of the sides of the casing by suitable cement or similar closure, 11, rendering the joints between the cover and 75 sides liquid proof. The casing and cover are formed from glass, hard rubber or any similar acid-resisting and electrically non-conducting material. By "acid-resisting" material, I mean material capable of resisting 80 acids of the strength of the solutions usually employed in storage batteries. Parts of the bottom or walls of the casing are formed from acid-resisting but electrically conductive material, and I prefer to make 85 such parts in the form of plugs or inserts, 12, of lead, which inserts are in electrical contact with the base of the thermostat and, through said base, with the thermostat bar.

The cover of the casing has a rabbeted 90 opening, 13, into which fits a shouldered plug, 14, and said opening and plug register with the head of the contact-screw, so that the latter may be adjusted from without, by removing the plug. Said plug is preferably 95 secured fluid-tight in its opening by a suitable cement, indicated by the numeral 15, which is fusible or soluble so as to be softened or dissolved to admit of the plug being removed without disturbing the remainder 100 of the casing. A binding screw, 16, is inserted with its lower end through an opening, 17, in the cover of the casing, and has a flange, 18, at about its middle. Said flange has annular ribs, 19, upon its under side, 105 which intermesh with similar annular ribs, 20, forming a seat upon the upper side or cover of the casing, and a gasket, 21, of rubber or

similar yielding material, resistant to the battery solution, is clamped between the ribbed flange and the seat. Similar annular ribs, 22, form a seat on the underside of the top or cover of the casing, and a yielding gasket, 23, is clamped against such seat by a washer, 24, having registering annular ribs, 25, and held in place by a nut, 26, upon the lower end of the screw.

10. A wire, 27, or similar conductor is secured to the thermostat contact-screw and to the binding-screw or post 16, and a binding-nut, 28, of acid-resisting and insulating material, fits upon the upper end of the binding-post. The binding screw and the washer 24 are formed from an electrically conductive and acid-resisting metal, and it is known that in practice, pure and unalloyed silver is the preferable material. The casing is filled 20 with a filling, 29, of an insulating and heat-conducting liquid, such as a liquid hydrocarbon, which makes a satisfactory and practical liquid, by means of which the elements within the casing are properly insulated, arcs formed between the contact points will be extinguished, and heat will be conveyed from the exterior of the casing to the thermostat bar.

Having thus described my invention, what 30 I claim as new and desire to secure by Letters Patent, is:—

1. A thermostat having an inclosing casing composed partly of electrically-conductive and acid-resisting material extending 35 from the exterior and in electrical connection with one contact of the thermostat and the remaining portion of said casing being

of electrically non-conductive but acid-resisting material.

2. A thermostat having an inclosing casing of acid-resisting and electrically non-conductive material, and externally exposed inserts in such casing of acid-resisting and electrically conductive material and connected to one contact of the thermostat.

3. A thermostat having an inclosing casing of acid-resisting and electrically non-conductive material, acid-resisting and electrically conductive externally exposed inserts in said casing, and two contacts, one of 50 which is electrically connected to said externally exposed inserts.

4. In a thermostat, an inclosing casing of acid-resisting and electrically non-conductive material, electrically conductive inserts 55 in a wall of said casing, a base plate within the casing and electrically connected to said inserts, a thermostat bar upon said base-plate and having a contact-point, a contact-screw insulated from the base-plate, a binding-post insulated from the casing, and a conductor connected to the binding-post and the contact-screw.

5. A thermostat having an inclosing acid-resisting casing of single thickness, part of 65 the outer surface of which is electrically non-conductive and part of such surface is electrically conductive and electrically connected to one contact of the thermostat.

GÜNTHER PHILIP WILD.
